United States Patent Office

Des. 208,599
Patented Sept. 12, 1967

208,599

BALLOT MARKER OR THE LIKE

Larry W. Lind, La Mesa, Calif., assignor to Cubic Corporation, San Diego, Calif.

Filed Oct. 4, 1965, Ser. No. 87,293

Term of patent 14 years

(Cl. D74—17)

FIG. 3

FIG. 1

FIG. 4

FIG. 2

FIG. 1 is a side view of the ballot marker or the like;
 FIG. 2 is a front view of the ballot marker or the like of FIG. 1;

FIG. 3 is a top view of the ballot marker or the like of FIG. 1; and

FIG. 4 is a bottom view of the ballot marker or the like of FIG. 1.

The appearance of the back is substantially identical to the front and the side not shown is substantially identical to the side shown in FIG. 1.

I claim:

The ornamental design for a ballot marker or the like, as shown and described.
